Claims priority, application Germany Mar. 10, 1959

4 Claims. (Cl. 167—42)

The present invention relates to and has as its objects new and useful compositions of organic fungicides, which contain in addition to known active fungicides certain special emulsifiers and other adjectives which render the inventive compositions highly active and especially stable. The special ingredients contained in the inventively improved fungicidal compositions are fatty alcohol polyglycol ethers or fatty acid polyglycol esters, metal salts, special magnesium salts of fatty acids and lower aliphatic or aromatic poly-basic carbonic acids or hydroxy carboxylic acids.

The use of organic fungicides for combating of fungous diseases especially for culture purposes during the last years became of increased importance. Since the number of organic fungicides is limited there has been done a great amount of work in the formulating of these fungicides to achieve thereby some effects which were not obtained by compositions known as yet. One method to find new compositions was to create finely divided metal of microsized particles. This could be performed by using special powder mills. Another method to obtain compositions of organic fungicides with improved properties is the use of special detergents, emulsifiers, special inert materials and the like. The purpose of improving known fungicides by a special formulation is not only to improve the activity, but also to broaden the time of activity and to give the compositions more rapid actions. It is known that as yet many organic fungicides regarding their immediate activity as well as their acute activity come within the range of the activity of inorganic metal compounds, especially copper fungicides. Sometimes they are even better than the latter. The disadvantage of organic fungicides regarding compatible copper sprays, however, is the fact that the time of activity is much shorter than the time of activity of copper compounds. This may be due to the reason that organic fungicides may be easier attacked by chemical influences than the extremely stable inorganic compounds.

It has been tried to improve the time of activity of organic fungicides by adding special compounds including detergents, emulsifiers, and the like. But as yet only very few formulations have been found which had an improved period of activity. Also some good compositions have been proven to be of special advantage only for one compound and the same composition could not be used advantageously regarding other organic fungicides. The cause for this fact might be due to the different mechanisms of action of the various organic fungicides. In the latter group there are as it is known two main classes of compounds. In one class the activity is due to the unchanged molecule, but other fungicides only act by their decomposition products, which are formed by hydrolysis, oxidation and other reactions on the plants.

Some auxiliary agents in fungicidal compositions especially detergents, emulsifiers, hydrophobating agents, adhesives act on the time of action and rapidity of action in a negative way. A theoretical example is the following: If an organic fungicide which acts by its decomposition products is brought into stable formulations, the particles are covered by water impenetrable layers and thereby the micro-particles are not able to be decomposed and there-

by they become inert or less biologically active on the plant.

In accordance with the present invention it has now been found that improved compositions of organic fungicides, especially improved fungicidal spray compositions broadly may be obtained, if as auxiliary solvents fatty acid metal salts and fatty acid polyglycol esters or fatty alcohol polyglycol ethers or aryl-polyglycol ethers are used. Additionally a certain amount of a solid lower

10 aliphatic di- or polycarboxylic acid or an aromatic carboxylic acid should be present in the inventive fungicidal compositions. Compositions of the above said type not only have a highly acute activity (rapid action), but they also render the organic fungicides a long lasting activity. 15 The compositions of the present invention also secure a good distribution on the plants. A redistribution on the sprayed plant organs by rain water also does not lead to such an amount as this is the case with other known fungicidal compositions.

20 The above mentioned polyglycol ethers may be an aryl-oxypolyglycol ether such as the reaction product of ethylene oxide or propylene oxide or mixtures thereof with phenol, the different cresols, and the like, hydroxy diphenyls (especially o- or p-hydroxydiphenyl), with 25 benzyl hydroxydiphenyl, and the like. Especially advantageous are fatty alcohol polyglycol ethers such as the reaction products of C₈ to C₂₅ alcohols especially C₁₂ to C₁₈ alcohols with ethylene oxide or propylene oxide or mixture thereof. Those reaction products are 30 e.g. lauryl, stearyl, palmityl or oleyl polyglycol ethers. Under polyglycol ethers there is to be understood a reaction product containing more than at least 2 glycol radicals in the molecule and usually not more than about 50 glycol radicals. Most suitable are the commercially 35 available polyglycol ethers containing in average between about 8 to 20 glycol radicals. The fatty acid glycerol esters as above mentioned should contain at least one unesterified OH-group. As examples there may be mentioned the lauric acid-glycerol-mono- and -diesters, the 40 palmitic acid-glycerol-mono- and -diesters, the stearic acid-glyceroldiester (Emocithin) and the like. Metal salts of fatty acids in the meaning of this invention are especially salts of C₈ to C₂₀ carbonic acids and should contain as a salt forming metal especially an alkaline earth metal (magnesium, calcium and the like), zinc, manganese, aluminium, iron, copper and the like. Especially useful organic acids are lauric, stearic, palmitic, 45 margaric, oleic, linoleic acid and the like.

50 Especially suitable solid lower aliphatic di- or polybasic acids which are useful for the inventively used compositions are oxalic acid, maleic acid, succinic acid, adipic acid, malic acid, citric acid, and the like. Aromatic acids are especially phthalic acid, salicylic acid, and the like.

55 Organic fungicides which may be formulated with the inventively used compositions are broadly the known compounds used in the field of plant protection as yet. As examples there may be mentioned at first the well known thio-carbamates (TMTD=tetramethyl-thiuram disulfide, ferrie dimethyl dithiocarbamate, manganese ethylene bis-dithiocarbamate, disodium ethylene bis-dithiocarbamate, zinc ethylene bis-dithiocarbamate, zinc dimethyl dithiocarbamate). Other examples are N-trichloromethyl mercapto-4-cyclohexene-1,2-dicarboximide, 2,3-dichloro-1,4-naphthoquinone, 2-heptadecyl glyoxalidine acetate, dinitro-(1-methyl heptyl)-phenyl-crotonate.

60 A special advantage of the inventively used combinations is the fact that this combination does not decrease the biological activity, but protects the active compound against influences which ordinarily make the active compound less efficient. It has even been found that the

biological activity is greater than the activity of formulations of known constituents used as yet for practical purposes. A further advantage is the increased period of activity of the inventively used compositions.

The inventive compositions usually contain the active ingredient in an amount of 5 to 95%, the balance being inert materials and the inventively used additional compounds. Usually the polyglycol ether or polyglycol ester compound is present in an amount of 1 to 25% more specifically 2 to 8%. The fatty acid salt in the inventively used compositions should be present in an amount of 1 to 15%, especially 2 to 10%. The solid hydroxy carboxylic, dicarboxylic or polycarboxylic acid at last is present in an amount up to 10%, especially in an amount of 2 to 8%. Inert materials used for the inventively described compositions are talc, chalk, kaoline, bentonite, kieselguhr and especially finely divided highly dispersable silicic acids in the form of their various commercially available brands.

The following examples are given to illustrate this invention without, however, restricting it in any way:

(1) Tetramethyl-thiuram-disulfide (TMTD):

- (a) 80.0% of tetramethyl-thiuram-disulfide
  - 4.3% of oleyl-polyglycol ether
  - 2.0% of magnesium stearate
  - 6.0% of colloidal kaoline
  - Rest finely divided silicic acid
- (b) 80.0% of tetramethyl-thiuram-disulfide
  - 3.0% of oleyl-polyglycol ether
  - 1.0% of magnesium stearate
  - 10.0% of adipic acid
  - Rest silitine Z (finely divided silicic acid, commercially available)
- (c) 60.0% of tetramethyl-thiuram-disulfide
  - 8.0% of oleyl-polyglycoether
  - 15.0% of magnesium stearate
  - 3.0% of finely divided silicic acid, and
  - Rest finely divided silicic acid

(2) Zinc-ethylene-bis-dithiocarbamate (ZINEB):

- (a) 80.0% of zinc-ethylene-bis-dithiocarbamate
  - 4.5% of oleyl-polyglycol ether
  - 2.0% of magnesium stearate
  - Rest finely divided silicic acid
- (b) 60.0% of zinc-ethylene-bis-dithiocarbamate
  - 4.0% of oleyl-polyglycol ether
  - 2.0% of magnesium stearate
  - Rest finely divided silicic acid
- (c) 80.0% of zinc-ethylene-bis-dithiocarbamate
  - 3.0% of oleyl-polyglycol ether
  - 1.0% of magnesium stearate
  - 8.0% of salicylic acid
  - Rest finely divided silicic acid
- (d) 60.0% of zinc-ethylene-bis-dithiocarbamate
  - 15.0% of magnesium stearate
  - 10.0% of oleyl-polyglycol ether
  - Rest finely divided silicic acid

(3) Zinc-dimethyl-dithiocarbamate (ZIRAM):

- (a) 90.0% of zinc-dimethyl-dithiocarbamate
  - 2.0% of magnesium stearate
  - 4.0% of oleyl-polyglycol ether
  - Rest finely divided silicic acid

(4) 1-chloro-2,4-dinitro-naphthaline (CDN):

- (a) 50.0% of 1-chloro-2,4-dinitro-naphthaline
  - 5.0% of magnesium stearate
  - 5.0% of oleyl-polyglycol ether
  - 1.0% of naphthaline-sulfonate
  - Rest finely divided silicic acid
- (b) 75.0% of 1-chloro-2,4-dinitro-naphthaline
  - 2.0% of magnesium stearate
  - 4.0% of oleyl-polyglycol ether
  - 2.0% of zinc oxide
  - Rest finely divided silicic acid

(5) N - trichloro - methyl-thio-(dimethyl-aminosulfonic-acid-anilide):

- (a) 50.0% of N-trichloro-methyl-thio-(dimethyl-aminosulfonic-acid-anilide)
  - 4.0% of oleyl-polyglycol ether
  - 1.0% of magnesium stearate
  - 8.0% of salicylic acid
  - Rest finely divided silicic acid
- (b) 50.0% of N-trichloro-methyl-thio-(dimethyl-aminosulfonic-acid-anilide)
  - 10.0% of magnesium stearate
  - 5.0% of decyl-polyglycol ether
  - 8.0% of salicylic acid
  - Rest finely divided silicic acid

An identical composition may be prepared from: N-trichloro-methyl - mercapto - 4-cyclo-hexene-1,2-di-carboximide.

(6) p-chloro- ω -rhodano-aceto-phenone:

- (a) 50.0% of p-chloro- ω -rhodano-aceto-phenone
  - 6.0% of oleyl-polyglycol ether
  - 5.0% of magnesium stearate
  - 5.0% of finely divided silicic acid
  - 2.0% of mineral oil fraction SAE 10
  - Rest colloidal kaoline
- (b) 50.0% of p-chloro- ω -rhodano-aceto-phenone
  - 6.0% of oleyl-polyglycol ether
  - 5.0% of magnesium stearate
  - 5.0% of Na₂HPO₄
  - Rest colloidal kaoline
- (c) 50.0% of p-chloro- ω -rhodano-aceto-phenone
  - 4.3% of oleyl-polyglycol ether
  - 3.6% of magnesium stearate
  - 3.6% of olive oil
  - 14.0% of finely divided silicic acid
  - Rest colloidal kaoline
- (d) 50.0% of p-chloro- ω -rhodano-aceto-phenone
  - 4.3% of oleyl-polyglycol ether
  - 3.6% of magnesium stearate
  - 3.6% of olive oil
  - 5.0% of citric acid
  - Rest finely divided silicic acid.

In the following the superiority of the inventively used compositions regarding their acute activity and resistance to rain leaching is demonstrated with some organic protective fungicides on Phytophthora infestans (late blight, tomatoes).

The following method has been adopted: in the green house young tomato plants grown under standard conditions (soil, temperature, humidity and light) are used after the 4 to 5 first leaves are formed. The plants are then sprayed by normal means to running off with inventively used compositions in an aqueous dilution of 55 the concentration shown in the tables below.

Thereafter they are placed for 24 hours in the green house to become dry (23° C.) (70 to 75% relative humidity). Thereafter they are inoculated with zoospores of the fungus in bidistilled water. The plants then are placed for 5 days in a humidity chamber at 100% relative humidity and at a temperature of 18 to 20° C. The plants treated as well as the inoculated plants during incubation are randomized in the humidity chamber. After the test is terminated the non-treated check plants are completely destroyed by the fungus. The plants treated are evaluated by counting each leaf according to the destruction, whereby 6 values are used. According to this standard measure number the evaluation number may be obtained and compared with a non-treated control 70 which is set 100. The evaluation numbers in the tables below thus give infestation in percent of the check.

If tested for resistance to rain leaching the plants when the spray is dried are sprayed by a finely divided measure spray of distilled water, corresponding to a quantity of 75 10 mm. rain during 10 minutes, on a turning table. The

sprayed plants then are dried and thereafter inoculated as described above. The plants thus treated and the plants non-sprayed (or rained) are artificially infested by the method given above. The other procedure is the same as described before.

EXAMPLE 1

Tetramethyl-Thiuram-Disulfide (TMTD)

TEST (a)

	Active ingredient concentration, percent	Evaluation number
		10
Normal formulation (commercially available)-----	{ 0.025 0.0125	{ 25 27
Inventive combination 1a-----	{ 0.025 0.0125	{ 11 24

TEST (b)

We claim:

1. Fungicidal compositions containing an organic fungicide in an amount from 5 to 95% together with
  - (a) 2 to 10% of a member selected from the group consisting of phenyl hydroxy polyglycol ethers, fatty acid polyglycol esters and fatty alcohol polyglycol ethers, the fatty alcohols and acids having 8 to 25 carbon atoms and being esterified with up to 50 glycol residues, and
  - (b) 1 to 10% of fatty acid metal salts, the fatty acid having 8 to 25 carbon atoms and the metal being a member selected from the group consisting of calcium, magnesium, zinc and aluminium, and
  - (c) up to 10% of a solid organic acid, this acid being a member selected from the group consisting of a lower aliphatic dicarboxylic acid, a lower aliphatic hydroxy-carboxylic acid and salicylic acid,
  - (d) the balance being inert filler.
2. Fungicidal compositions containing an organic fungicide in an amount from 5 to 95% together with
  - (a) 2 to 10% of fatty alcohol polyglycol ethers, the fatty alcohol having 12 to 18 carbon atoms and being esterified with up to 50 glycol residues, and
  - (b) 1 to 10% of fatty acid metal salts, the fatty acid having 12 to 18 carbon atoms and the metal being a member selected from the group consisting of calcium, magnesium, zinc and aluminium, and
  - (c) up to 10% of a solid organic acid, this acid being a member selected from the group consisting of a lower aliphatic dicarboxylic acid, a lower aliphatic hydroxy-carboxylic acid and salicylic acid,
  - (d) the balance being inert filler.
3. Fungicidal compositions containing an organic fungicide in an amount from 5 to 95% together with
  - (a) 2 to 10% of stearyl alcohol polyglycol ether being esterified with 5 to 25 glycol residues, and
  - (b) 1 to 10% of magnesium stearate, and
  - (c) up to 10% of a solid organic acid, this acid being a member selected from the group consisting of a lower aliphatic dicarboxylic acid, a lower aliphatic hydroxy-carboxylic acid and salicylic acid,
  - (d) the balance being inert filler.
4. Fungicidal compositions containing an organic fungicide in an amount from 5 to 95% together with
  - (a) 2 to 10% of palmityl alcohol polyglycol ether being esterified with 5 to 25 glycol residues, and calcium palmityl polyglycol ether, and
  - (b) 1 to 10% of magnesium palmitate, and
  - (c) up to 10% of a solid organic acid, this acid being a member selected from the group consisting of a lower aliphatic dicarboxylic acid, a lower aliphatic hydroxy-carboxylic acid and salicylic acid,
  - (d) the balance being inert filler.
